UNITED STATES PATENT OFFICE.

HARRY R. HEAL, OF CAMDEN, NEW JERSEY.

COUNTER.

SPECIFICATION forming part of Letters Patent No. 690,424, dated January 7, 1902.

Application filed October 15, 1901. Serial No. 78,719. (No model.)

To all whom it may concern:

Be it known that I, HARRY R. HEAL, a citizen of the United States, residing at Camden, in the county of Camden and State of New Jersey, have invented certain new and useful Improvements in Counters for Printing-Presses and other Purposes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in counting mechanism for printing-presses and other purposes wherever a registration of mechanical results or action may be required.

The objects of the invention are, first, to provide a mechanism or device of a simplified, effective, and inexpensive construction for automatically counting, registering, and indicating the number of impressions made by a printing-press, and, second, to provide a mechanism of the kind named and for the purposes intended wherein the use of gearings heretofore commonly employed to connect successively-actuated indicating-disks is avoided.

With these objects in view the invention consists in the novel construction of parts and their arrangement and aggroupment in operative combination, as will be hereinafter fully described and the novelty thereof particularly pointed out and distinctly claimed.

I have fully and clearly illustrated my invention in the accompanying drawings, forming a part of this specification, and wherein—

Figure 1 is a vertical sectional view through the casing and face view of the counting-disks, two whereof are partly broken away to show the supporting-shaft. Fig. 2 is a transverse section through one end of the machine-casing and side elevation of the actuating-lever and disk. Fig. 3 is a detail side elevation illustrative of the operation of releasement of the locking-pawl by the pin in the disks. Fig. 4 is a detail perspective of one of the locking-pawls.

Referring to the drawings, 1 designates a metal casing of suitable shape and of a ca-

pacity to contain the operating mechanism and is formed with perforated ears 2, by which it may be secured to a support. The 55 end walls of the casing 1 are formed with bearings 3, in which is mounted a shaft 4, and in bearings 5 at the lower portion of the casing is mounted a stationary shaft 6 for the purposes 60 hereinafter mentioned.

On the shaft 4, adjacent to one end of the casing, is pivotally mounted a lever 7, formed with a vertical arm 8, to the end of which is pivotally hung a pawl 16 to successively engage the teeth of a disk 10. To the outer 65 end of the lever, which projects outward from the casing through a vertical slot a, is connected the end of a spiral spring 18, to the lower end of which is fastened a rod 18^a, leading to and operatively connected to 70 the press (not shown) in a well-known manner. To the end of an arm 7^a of the lever, extending rearward, is hung a weight 9, and adjacent to the end of the arm 7^a is attached a cord 17, which is carried over a sheave 17^a 75 and continued to some convenient point for manipulation, the object being that when the cord is released the weight will carry the lever down to release the pawl and hold it out of engagement and prevent operation of the 80 counting mechanism. The pressman then secures the cord to a convenient place, to remain until the lever is required to resume the count. The force of the weight also acts to return the pawl to normal position after the 85 actuating-arm of the lever has been drawn down. The movement of the lever is limited by stop-pins (not shown) placed in the wall of the casing at the desired points and projecting into the walls of the arm 8.

On the shaft 4 are mounted a plurality of ratchet-disks 10, 11, 12, 13, and 14. Five of these disks are shown; but it is apparent that a less number or greater may be used to accommodate the determined capacity of the 95 counter. The initial or primary disk 10 is fixed to the shaft 4 by any proper means, while the others are held by frictional contact alone and arranged to be turned with the shaft when the locking-pawl of any one of 100 them is released. The teeth of each disk are consecutively numbered on their faces, as shown in Fig. 1 of the drawings, and at the hub or shaft opening are formed with annu-

lar flanges or bosses 15, which when the disks are operatively mounted contact with each other and separate the side faces of adjacent disks.

5 On the fixed shaft 6 are fulcrumed a plurality of locking and tripping levers 19, each of which is slit longitudinally at the front portion to form a pawl 20 and a downwardly-curved tripping-arm 21. The levers 19 are 10 provided with depending ears 22, perforated to engage over the shaft 6, and are held against lateral displacement by means of interposed and end washers 19^a, as indicated in the drawings.

15 Each of the counting-disks is provided with a projecting pin 23, said pins being so relatively located as to engage with the curved tripping-arms 21 at predetermined intervals.

20 The operation of the counting mechanism may be stated as follows: The disks being arranged with the naughts at initial position, then at each downward movement of the lever 7 through its connections with the press the pawl 16 turns the disk 10 the distance of one tooth and presents the initial number to visual observation at an opening in the case intended for that purpose, and when the disk 10 has made a full revolution the pin 23 in the disk contacts with the curved trip-arm 21, 25 which lies below the disk 10, and releases the locking-pawl 20 from its engagement with disk 11 to permit that disk to turn the distance of one tooth. After the disk 11 has been turned one complete revolution its pin 30 23 will in like manner unlock the next adjacent disk 12, and so on for all the disks.

35 The distinguishing feature of the invention is that the frictional contact of the disks with the shaft 4 is the only means for effecting their 40 rotation with the shaft when the period of their revolution arrives, and thus no supplemental gearing is required.

What I claim is—

1. In a counting-machine, a rotary shaft, a 45 ratchet counting-disk fixedly mounted thereon and provided with numerals on the face of the ratchets, and a tripping-pin projected ra-

dially from one of the ratchets, an adjacent ratchet-disk mounted on the said shaft to turn therewith by frictional contact, a pawl to engage the second ratchet-disk and formed with a tripping-arm in the path of the pin in the first ratchet-disk. 50

2. In a counting-machine, the combination of a rotating shaft, a counting-disk having peripheral ratchets and numerals thereon, a plurality of counting-disks mounted on the shaft to turn therewith by frictional contact, and having numbers on the ratchets, pawls to lock each of the frictionally-mounted disks 60 against rotation and to be released by means on the adjacent disk, substantially as described. 65

3. In a press counting-machine, a rotating shaft, a ratchet-disk fixed on the shaft, a lever to intermittently rotate the disk the length of one ratchet at a time, a second ratchet-disk frictionally mounted on the shaft, a pawl to hold the second disk against rotation, and means on the first disk to release the pawl and permit the second disk to rotate with the shaft. 70

4. In a counting-machine, the combination with a casing formed with bearings, a rotatable shaft journaled in said bearings, a counting-disk fixedly mounted on said shaft, a plurality of disks held on the said shaft by frictional contact, and formed with peripheral ratchet-teeth, a lever mounted on said shaft and having an upwardly-extending arm, means for operating said lever to turn the disk the length of one ratchet, means for connecting said lever to a moving part of the machine, a pawl secured to said upwardly-extending arm to engage the ratchet of the first disk, a stationary shaft in the casing below the disks, pawls to lock the frictionally-mounted disks on the rotatable shaft, and pins to release the pawls in determined succession. 75 80 85

5. In testimony whereof I affix my signature in presence of two witnesses.

HARRY R. HEAL.
